FOLDING WHEEL CHAIR

Robert E. Lee, Alexandria, Va., assignor to
Anthony G. Allison, Chicago, Ill.

Application September 10, 1953, Serial No. 26,756

Term of patent 14 years

(Cl. D15—1)

To all whom it may concern:

Be it known that I, Robert E. Lee, a citizen of the United States, and a resident of Alexandria, in the State of Virginia, have invented a new, original, and ornamental Design for Folding Wheel Chair, of which the following is a specification, reference being had to the accompanying drawings, forming a part hereof.

Figure 1 is a perspective view of a folding wheel chair embodying my new design, the view showing the chair in an extended in-use position; and

Figure 2 is a perspective view of the folding wheel chair, the view showing the chair in an extended in-use position and including leg rests, the leg rests and foot rests of the chair being elevated.

The side opposite to the side of the folding wheel chair shown is substantially the same in appearance.

I claim:

The ornamental design for a folding wheel chair, as shown and described.
